Initially disclosed in the United States Patent Office, this invention relates to ash tray holders and particularly covers a device which is designed to be mounted on various supports such as the standards of floor lamps, bird cage stands, vertical pipes, etc.

UNITED STATES PATENT OFFICE

2,377,560

ASH TRAY HOLDER

Rudolph C. Kulling, Chicago, Ill.

Application October 26, 1944, Serial No. 560,497

2 Claims. (Cl. 248—230)

The present invention relates to new and useful improvements in ash tray holders, and has for its primary object to provide, in a manner as hereinafter set forth, a device of this character comprising novel attaching means whereby the holder may be readily mounted for use on various supports which are usually at hand in households, such, for example, as the standards of floor lamps, bird cage stands, vertical pipes, etc.

Other objects of the invention are to provide an ash tray holder of the aforementioned character which will be comparatively simple in construction, strong, durable, highly efficient and reliable in use, compact, and which may be manufactured at low cost.

All of the foregoing and still further objects and advantages of the invention will become apparent from a study of the following specification, taken in connection with the accompanying drawing wherein like characters of reference designate corresponding parts throughout the several views, and wherein:

Figure 1 is a plan view of an ash tray holder constructed in accordance with the present invention.

Figure 2 is a view in side elevation of the device, showing a tray mounted therein.

Figure 3 is a vertical sectional view, taken substantially on the line 3—3 of Figure 1 with a portion of the tray-receiving ring broken away.

Figure 4 is a fragmentary view in horizontal section, taken substantially on the line 4—4 of Figure 2.

Referring now to the drawing in detail, it will be seen that the embodiment of the invention which has been illustrated comprises a metallic ring 1 of suitable diameter. The ring 1 is for the reception of a conventional ash tray 2.

The ring 1 is welded or otherwise suitably fixed on the bight portion 3 of a substantially U-shaped bracket of suitable metal which is designated generally by reference numeral 4. Connecting the free end portions of the legs 5 of the substantially U-shaped bracket 4 is a pair of spaced, parallel bars 6 and 7. Also extending between the legs 5, on one side of the bracket 4, is a plate 8.

Mounted on the bracket 4 is an attaching clamp 9. The clamp 9 includes a resilient metal band 10 having one end secured to the bar 6 of the bracket 4 (see Figure 4). The band 10 is adapted to be tightened around a suitable support, such as the standard of a floor lamp, for mounting the holder thereon.

The other end portion of the band 10 has

formed therein spaced openings 11 and is rolled on or wrapped around a flat core 12 which is engageable in the bracket 4 between the legs 5 thereof. The core 12 has formed therein an opening which is aligned with the openings 11 in the portion of the band 10 which is wrapped around said core. The aligned openings in the core 12 and the band 10 accommodate a bolt 13 which is threaded through an opening 14 provided therefor in the plate 8. A resilient guide 15 is mounted on the bar 7 for directing the apertured end portion of the band 10 into the bracket 4 when the bolt 13 is tightened.

In use, the band 10 is contracted around a suitable support and frictionally clamped thereon by tightening the bolt 13 in the bracket 4. When this occurs, the end portion of the resilient band 10 which is wound or wrapped around the core 12 is drawn into the bracket 4, as seen in Figure 4 of the drawing. Of course, by loosening the bolt 13, the clamp 9 may be readily adjusted to any desired position on the support. The construction and arrangement is such that all ordinary adjustments may be readily accomplished by simply screwing the bolt 13 inwardly or outwardly. When a major adjustment of the clamp 9 is necessary, the bolt 13 is removed and the apertured end portion of the band 10 is unwound from or wound on the core 12, as the case may be, thus increasing or decreasing the diameter of said band 10. With the band 10 around the support on which the holder is to be mounted, the bolt 13 is re-inserted and tightened for clamping said band on said support. Although the device is particularly intended for ash trays, it may, of course, be used for holding any other receptacle or articles for which it may be found adapted.

It is believed that the many advantages of an ash tray holder constructed in accordance with the present invention will be readily understood, and although a preferred embodiment of the device is as illustrated and described, it is to be understood that changes in the details of construction may be resorted to which will fall within the scope of the invention as claimed.

What is claimed is:

1. An ash tray holder comprising a bracket, an apertured core, a resilient band including an end portion wrapped around the core and having spaced openings therein aligned with the aperture in said core, the other end of the band being anchored to the bracket, a bolt engaged in the aligned aperture and openings in the core and the band and threaded to the bracket.

et for adjustably securing the band thereto, and means for mounting an ash tray on the bracket.

2. An ash tray holder of the character described comprising a substantially U-shaped bracket, a bar extending between the free end portions of the legs of the bracket, a plate extending between the legs of the bracket, a core operable between the legs of the bracket, said core having an opening therein, a resilient band including an end portion wrapped around the

core and having spaced openings therein aligned with the core opening, the other end of the band being connected to the bar, a bolt engaged in the aligned openings in the core and the band and threadedly mounted in the plate for adjustably connecting said one end portion of said band thereto, and a ring, for the reception of an ash tray, fixed on the bracket.
